UNITED STATES PATENT OFFICE.

NIC KRUMP, OF CHICAGO, ILLINOIS.

SHEET-METAL BRAKE.

1,203,206.

Specification of Letters Patent. Patented Oct. 31, 1916.

Application filed September 3, 1915. Serial No. 48,927.

To all whom it may concern:

Be it known that I, NIC KRUMP, a citizen of the United States, and a resident of Chicago, in the county of Cook and State of Illinois, have invented certain new and useful Improvements in Sheet-Metal Brakes, of which the following is a specification.

This invention relates to devices for bending sheet metal and used by sheet metal workers, and known in the sheet metal art as brakes.

The object of this invention is to obtain a sheet metal brake which is adapted to bend sheets of metal of various thickness; to obtain a device in which sheets of metal will be held firmly and bent on a determined line; and to obtain a power driven device of the kind named wherein a sheet holding mechanism, while adapted to be applied to hold a sheet of metal rigidly in place, will not be broken by the lack of skill or inattention of the person or persons operating the same. And a further object is to obtain a holding mechanism in a brake of the character described which may be set, so that when a large number of sheets of metal of the same thickness are to be bent the said holding mechanism will be automatically disconnected from the motive power which is applied thereto to obtain a desired grasp or hold on the sheet of metal which is to be bent.

In bending the edge of a sheet or strip of metal of considerable length, say one exceeding nine or ten feet, I find it desirable to be able to independently control the holding mechanism at the ends of said sheet or strip, so that when the said sheet or strip is properly in place at one of its ends said end can be held, while the other end is moved a short distance to the proper position for said bend. In operating a device I find it desirable to provide means whereby what may be termed an automatically controlled grasp by said holding means, at one end of said sheet, may be applied thereto, said automatic grasp being such as to permit movement of the sheet of metal at the other end.

In the drawings referred to as forming a part of this specification, Figure 1, is a perspective of a brake provided with holding mechanism embodying this invention. Fig. 2 is an end view of said brake, showing a mechanism embodying this invention thereon, with a portion of a worm driven wheel which forms an element of said mech-

anism removed, to expose to view a cam and a cam shaft, which are also elements of the mechanism. Fig. 3 is a vertical sectional view of a link, cam and worm wheel and a side elevation of the shafts thereof, said section being taken on line 3—3 of Fig. 2 and viewed in the direction indicated by the arrows. Fig. 4 is a front view of said link. Fig. 5 is an end elevation of a clutch sleeve forming an element of mechanism embodying the invention. And Fig. 6 is a side elevation of said clutch sleeve.

A reference character applied to designate a given part indicates said part throughout the several figures of the drawing wherever the same appears.

A, A¹ represent standards forming the ends of the brake.

B, Fig. 2, is a table on which sheets of metal to be bent may be laid.

C is an apron which is turned on shaft D; and E (Fig. 1), is an angle-iron which is rigidly secured to the upper edge of the apron C, and by means of which a sheet of metal which is placed on table B and held rigidly thereto, by the mechanisms embodying this invention, is bent.

F is a movable body which is mounted to rock on shaft f in slot f¹, forming the upper jaw of the clamp of the brake, and said upper jaw is provided at the forward and holding edge thereof with the holding or grasping plate G.

The sheet of metal to be bent is placed on table B and is brought out in front of the holding plate G and rigidly held by said plate G as apron C and angle iron E are turned on shafts D, and said angle iron E bends said sheet.

The mechanism by means of which the upper jaw F and holding or grasping plate G are moved, to raise said plate G from, and bring it to, a sheet or strip of metal which is to be held thereby and bent by apron C and angle iron E, embodies this invention. Said mechanisms are positioned on standard A, at both ends thereof, and are duplicates (but may be rights and lefts) and each of said mechanisms comprises the following described parts.

H represents a shaft which is secured to standard A; h represents a spur shaft which is secured to the upper jaw F.

I represents a link, J a cam and K a worm wheel.

L, L¹, L², represent shafts journaled in

bearings M, and M¹ M¹ and M² and M², respectively.

L³ represents a driving shaft which is journaled in suitable bearing on standards 5 A A', and N a beveled gear, which is rigidly secured to driving shaft L³.

n represents a beveled gear intermeshing, with gear N. Beveled gear n and gear n¹ are connected or joined to turn in unison, 10 and are mounted loosely on shaft L.

N¹ and n² represent gears which are rigidly secured on shaft L¹, to turn therewith.

N² is a gear wheel on shaft L² and N³ is a gear wheel which is loosely mounted on 15 shaft L. Gears n¹, N¹ intermesh; and also gears n², N² and N³.

n³ is a worm wheel which is secured on shaft L to turn therewith.

The function of gears n¹ and N¹, n² N² is 20 to drive gear N³, in the opposite direction to that in which the beveled gear n is turned by beveled gear N. The clutch wheel P is keyed on shaft L to turn therewith while longitudinally movable thereon; said longitudinal movement being controlled by the 25 handle Q which is pivoted to standard A at q. The clutch wheel P is provided with the groove p, in which said handle Q fits and with the clutch teeth p¹ and p².

30 R is a clutch wheel rigidly secured to the gear wheel n¹ to turn therewith and r is a clutch wheel which is rigidly secured to the gear wheel N³ to turn therewith.

The handle Q is moved down to force the 35 clutch P into gear with clutch R, and bring the holding bar G of the upper jaw F down into holding or grasping position on a sheet of metal on table B; and said handle is moved up to force said clutch P into gear 40 with clutch r to raise said holding bar G from said grasping position. The clutches R and r, turning in opposite directions, as hereinbefore described, enable me to move the grasping bar G down and up the required 45 distance to operate it, by rocking said worm gear K and cam J on their shaft. That is, they are not rotated or caused to turn a complete revolution. When the handle Q is moved down from the position 50 illustrated in Fig. 2, the clutch teeth p¹ on clutch P, are forced into engagement with the teeth of clutch wheel R and when said handle is moved up from said illustrated position the clutch teeth p² are moved 55 into engagement with the teeth of clutch wheel r.

Sheets or strips of metal of different thicknesses are bent or folded on the brake 60 illustrated, and to prevent breaking of the mechanism embodying this invention, (when said holder is pressing with determined force on the sheet or strip of metal thereunder), the engaging faces of the clutch teeth p¹ and the teeth on clutch R are made of such shape 65 that the same can not be held in engage-

ment, by a person grasping the handle Q, after a predetermined pressure of bar G is obtained said handle being forced upward by said engaging faces. Of course, upon the handle Q being forced up as aforesaid, the 70 person holding it down and feeling the upward movement thereof, will not resist the same; on the contrary being thereby notified or warned, he will raise the handle Q. However, if said engaging faces are at substantially 75 an angle of about 45 degrees from a plane at right angles to shaft L the above named results are obtained, and breaking of the device is obviated. Grasping bar or plate G being down and the handle Q in its 80 normal position (as illustrated in Fig. 2), to release and raise said grasping bar the handle Q is raised to engage clutch P with the teeth of clutch r; and to obtain quick release of said engagement I make the engaging 85 faces of the teeth on said clutches at the same angle as those of clutch R and teeth p¹.

In addition to the above named means for automatically throwing the clutch wheel P out of engagement with clutch R, I provide 90 additional automatic means for throwing said clutch out of engagement, on the downward movement of the upper jaw, when it has reached a desired downward position.

Said additional means comprises screw 95 threaded bolts S extending through an aperture provided therefor in handle Q, said bolt being attached loosely at its upper end to worm wheel K, as by pin T, and adjustable nuts u on said bolt S. The position of said pin T (which is rotatable) relative to the cam J is indicated by the broken lines T in Fig. 2. While the worm gear K is turning clockwise and bringing the link I and jaw F down, the pin T is being moved up and is carrying therewith bolt S, and the nuts u are adjusted on said bolt S so that the said upward movement of the bolt brings said nut into contact with the under side of said handle, (to raise it to its normal and neutral position, with said clutch P out of gear), when the grasping or holding bar G is in its desired downward position.

It will be observed that when the handle Q is raised to bring the teeth p² of clutch P into engagement with clutch wheel r the direction of revolution of worm n³ is reversed so that the worm gear wheel K turns in a direction contrary to the movement of the hands of a clock and thereby the bolt S is moved downward, and U are nuts on bolt S which are adjusted on said bolt to come in contact with the upper face of handle Q and force said handle down thereby breaking the engagement of clutches P and R when cam J has raised said jaw F a predetermined distance.

The contact faces of the teeth of clutch wheels P, R and r, respectively, being, as hereinbefore stated, at an angle (about 45

degrees) to the face of a disk on the shaft L, constitute a sliding engagement; that is, as against sufficient resistance the said contact faces will slide upon each other and move 5 the handle Q as said clutches move out of engagement. In addition to this, said faces being sliding faces it is necessary for the person controlling the position of clutch P to retain hold of handle Q at all times, and 10 when said clutches P and r are in engagement handle Q can be easily moved downward by the operator, as the contact faces of the teeth on clutch r do not grip or hold in the manner in which the same would grip 15 or hold if said contact faces were in a plane radial to shaft L.

The mechanism which is positioned at the farther end of the brake illustrated in Fig. 1 is provided with members corresponding 20 with the members illustrated in Figs. 1 and 2 and the description hereinbefore given applies to said duplicate or corresponding mechanism.

I claim:—

25 1. In a power driven device, to control the movement of the movable jaw of a brake, the combination of a driving and a driven shaft, clutches loosely mounted on said driven shaft, means on said driving shaft 30 engaging with means on said driven shaft to turn said clutches in opposite directions, an additional clutch mounted on said driven shaft to turn therewith and longitudinally movable thereon, a handle adapted to move 35 said additional clutch to alternately engage with said first named clutches, an eccentric, a link attached at one end to said movable jaw and mounted at the other end on said eccentric, and means connecting said driven 40 shaft and said eccentric to communicate swinging movement to said eccentric by the rotation of said driven shaft in opposite directions.

2. In a power driven device, to control 45 the movement of the movable jaw of a brake, the combination of a driving and a driven shaft, clutches loosely mounted on said driven shaft, means on said driving shaft engaging with means on said driven 50 shaft to turn said clutches in opposite directions, an additional clutch mounted on said driven shaft to turn therewith and longitudinally movable thereon, a handle adapted to move said additional clutch to 55 alternately engage with said first named clutches, an eccentric, a link attached at one end to said movable jaw and mounted at the other end on said eccentric, and means con-

necting said driven shaft and said eccentric to communicate swinging movement to said eccentric by the rotation of said driven shaft 60 in opposite directions.

3. In a brake, a movable jaw, a standard, a rotatable shaft, mounted in journals on said standard, and a handle also mounted on 65 said standard, a worm and a clutch mounted on said shaft to turn therewith, said clutch longitudinally movable, and arranged to move and to be moved by said handle, gear wheels loosely mounted on said shaft and 70 clutch wheels attached to said gear wheels, a driven shaft rotatably mounted on said standard, a gear wheel on said driven shaft arranged to rotate said loosely mounted gears and clutches in opposite directions by 75 the rotation of said driving shaft, in combination with a worm wheel, an eccentric joined thereto, said worm wheel mounted on said standard with its teeth engaging with said worm, and a link attached at one end 80 to said movable jaw and at the other end arranged to engage with said eccentric.

4. In a brake, a standard, a movable jaw and an eccentric mounted on said standard, in combination with a link connected at one 85 end to said movable jaw and at the other end arranged to engage with said eccentric, means comprising a clutch member movable from a neutral to operative positions to turn said eccentric in opposite directions, and a 90 plurality of means to limit said turning, one of said limiting means comprising mechanism to automatically force said movable clutch member from an operative into a neutral position, and the other comprising 95 engageable faces on said movable clutch member so disposed as to automatically disengage when more than a predetermined load is presented thereto.

5. In a power driven device to control the 100 movement of the movable jaw of a brake, a cam, a link pivotally attached at one end to said jaw and arranged to engage with said cam, means to turn said cam in opposite directions, a handle provided with an 105 aperture, a bolt extending through said aperture in said handle, a connection between the upper end of said bolt and said cam, and nuts adjustably mounted on said bolt and adapted to be forced on to said handle, to 110 move said handle when said cam is moved into predetermined positions.

NIC KRUMP.
